UNITED STATES PATENT OFFICE.

ERASTUS F. BRADFORD, OF BOSTON, MASSACHUSETTS.

IMPROVEMENT IN PAPER COLLARS.

Specification forming part of Letters Patent No. **170,336**, dated November 23, 1875; application filed June 24, 1875.

To all whom it may concern:

Be it known that I, ERASTUS F. BRADFORD, of Boston, in the county of Suffolk and State of Massachusetts, have invented an Improved Paper Collar, of which the following is a specification:

This invention relates to paper collars; and consists in a loop formed as part of or attached to the collar, for the purpose of holding the neck-tie in position within the fold of the collar, substantially as described.

Figure 1 is a perspective view of a collar with the end closed, as if about the neck, and with the neck-tie in position. Fig. 2 is a back view of the collar unfolded.

The collar is made to fold on the line *a*. The part *b* is made to turn over as a turn-down collar, and its edges *c d* are folded inwardly, as shown. In the folded parts *d* are formed notches constituting loops *e e*, through which

the neck-tie *f* is passed, as shown in Fig. 2, and when the part *b* is turned down the neck-tie is retained up closely into the fold of the collar, and as shown in Fig. 1.

In case a button is broken off, the neck-tie being held in position will hold the collar, and prevent it rising away from the tie.

I claim—

As a new article of manufacture, a paper collar, provided with loops in the folded parts *d*, substantially as described, to hold the neck-tie in position, as set forth.

In testimony whereof I have signed my name to this specification in the presence of two subscribing witnesses.

ERASTUS F. BRADFORD.
